CORD TAP ASSEMBLING MACHINE

Sidney M. Weisberg, Newark, N. J., assignor to Allied Electric Products, Inc., Irvington, N. J., a corporation of New Jersey

Application June 7, 1950, Serial No. 166,586

4 Claims. (Cl. 29—206)

The invention disclosed in this patent is a machine for assembling multiple service taps on the ends of extension cords.

Special objects of the invention are to provide a machine of simple, practical construction, easy to understand and operate and which will effect the assembly of the parts rapidly and accurately and without distortion or injury to the parts.

A special feature of the invention is the mechanism designed to open up the tap body to receive the cord and the contacts on the end of the cord.

It has been an object in designing this mechanism to assure first that the tap body which is usually of rubber or like stretchable material, will not be stretched beyond a desired limit and second, will not be held in the stretched-open condition long enough to weaken or injure the material.

Other desirable objects attained by the invention and the novel features contributing to the invention are set forth or will appear in the course of the following specification.

The drawings accompanying and forming part of the specification illustrate a present commercial embodiment of the invention. Structure, however, may be modified and changed, all within the true intent and broad scope of the invention as hereinafter defined and claimed.

Fig. 1 in the drawings is a broken plan view of one of the tap assembling machines;

Fig. 2 is an enlarged broken plan view of the central spreader portion of the machine, showing a tap body in distended condition and with the contacts inserted therein;

Fig. 3 is a further enlarged cross sectional view taken on substantially the plane of line 3—3 of Fig. 2, showing the tap body fully distended by the four spreader fingers and with the contacts entered through the opened throat of the tap body;

Figs. 4, 5 and 6 are sectional views of the assembled tap, Fig. 4 as on the plane of line 4—4 of Fig. 6, Fig. 5 as on the plane of line 5—5 of Fig. 4, and Fig. 6 as on the plane of line 6—6 of Fig. 4;

Fig. 7 is a broken cross sectional view as on substantially the plane of line 7—7 of Fig. 1, showing a tap body as first located over the spreader fingers and with the parts in the starting position illustrated in Fig. 1;

Fig. 8 is a broken cross sectional view on substantially the plane of line 8—8 of Fig. 7;

Fig. 9 is a broken sectional view similar to Fig. 7 but showing the upper and lower sets of spreader fingers separated to start the opening action;

Fig. 10 is a broken sectional detail showing the upper spreader fingers raised by the spreader cam as in Fig. 9;

Figs. 11 and 12 are plan and side elevation views, respectively, of the contact holder on the back slide, showing the wired contacts yieldingly and removably held in position thereon, ready for insertion into the tap;

Fig. 13 is a diagrammatic view showing the relation of the tap and spreader fingers when the tap body is first placed over those fingers, as in Fig. 7;

2

Fig. 14 is a similar view showing the parts as they appear when the tap body is turned over to the position shown in Fig. 9 and the upper and lower sets of fingers separated by rocking down the cam levers appearing at the top in this view;

Fig. 15 is a diagrammatic view showing the vertically spaced fingers separated laterally to effect the full opening of the tap body to the extent indicated in Figs. 2 and 3;

Fig. 16 is a diagrammatic view illustrating the action of stripping the assembled tap off the blades of the contact inserting slide.

The multiple outlet form of tap which the present illustrated machine is intended to handle, is shown in Figs. 4, 5 and 6 as comprising a one-piece body of rubber or similar elastic material 20 having an entry throat 21 in one end for the cord 22 and attachment blade receiving passages 23 in the opposite end and other attachment blade receiving passages 24 in the opposite sides of the same.

These end and side opening contact passages 23 and 24 cross inside the tap body and thus accommodate the cruciform type of contacts shown at 25. There are two of these, at opposite sides of the intermediate separating partition wall 26, the latter extending, as shown in Figs. 4 and 6, nearly up to the cord entrance 21 so as to form a separator for the two wires of the cord and a barrier separating the two contacts 25 attached to the ends of the wires at 27.

To locate these contacts and wires, the mouth of the tap body needs to be opened up at opposite sides of the central partitioning structure 26 an extent sufficient to pass the laterally projecting bar portions 28 of the contacts.

For such purposes spreader fingers are provided over which the mouth of the tap body may be forced and then these fingers are first opened up in one way to start the spreading action and then separated in a different direction to complete the spreading and opening action.

Fig. 1 shows the upper of the vertically and horizontally separable spreader fingers at 29, 30, and Figs. 7, 8 and 9 show the companion, lower, laterally separable fingers 31, 32.

The left and right-hand pairs of spreader fingers 29, 31 and 30, 32, respectively, are mounted on slides 33, 34, operable in a guiding structure 35 and shifted by rods 36, 37, connected with pistons 38, 39, in air cylinders 40, 41.

These pistons are acted on by springs 42, tending to return them to the position shown in Fig. 1, with the spreader fingers in laterally abutting or adjoining relation, and the pistons are actuated in the opposite, finger separating direction by air or other power fluid admitted through piping 43 to the front ends of the pistons under control of a foot valve 44 which may be a customary four-way ratchet foot valve.

The vertical separation of the fingers of each laterally separable pair is effected, in the illustration, by mounting the upper fingers 29, 30, on slides 45, 46, vertically operable in the laterally shifting slides 33, 34, Fig. 8, and arranged to be positioned by cams 47, 48, on rock shafts 49, 50, journaled on the laterally separable slides and operable by hand levers 51, 52.

To hold the tap body firmly in position while being opened up to receive the contacts, a plunger 53 is shown operable in a guide 54 by hand lever 55 to force the tap over the spreader fingers into engagement with the abutment surface 56, Fig. 2.

In the present disclosure the plunger 53 is retained in the holding position, Fig. 2, by means of a latch 57, Figs. 1 and 2, pivoted on lever 55 in position to engage over a detent lug 58. Latch lever 57 is arranged to be disengaged from the lug 58 by means of spring pressed release lever 59, Fig. 1.

The holder for the contact blades which are to be inserted, is shown in Figs. 11 and 12 as a reduced extension 60 on the inner end of a plunger slide 61 operable by a hand lever 62 and having spring fingers 63, 64, at the upper and lower sides of the same to yieldingly confine and retain the upper and lower tap contacts 25.

The front and back slides or plungers 53 and 61, Figs. 1 and 2, are supported for back and forth movement substantially at right angles to the lateral movement of the spreader slides 33 and 34.

Operation

Under typical conditions, with the front and back slides 53 and 61 retracted or withdrawn as in Fig. 1, a pair of the tap contacts 25 secured on the ends of an extension cord 22, may be slipped over the spring arms 65 of the contact holder 60, as shown in Figs. 11 and 12, with the attached cord 22 offset at the side of the holder.

Then, as shown in Fig. 7, the cord receiving end 21 of a tap body 20 may be slipped over the ends of the collapsed spreader fingers 29, 30, 31, 32, with the side outlets 24 upper and lowermost and the oval shape of the cord throat 21 therefore the more readily engageable over the fingers. In this position, however, the ends of the fingers will contact the end of the separating partition 26 in the tap body. The latter may then be rotated one-quarter turn to bring the side outlets 24 to opposite sides, as in Figs. 2 and 9, with the fingers positioned to upper and lower sides of said partition. Whereupon the hand levers 51, 52, may be rocked downwardly from the Figs. 1, 7 and 8 position to the Figs. 2, 9 and 10 position, to raise the upper fingers 29, 30, and open up the cord receiving throat 21 from the Fig. 13 to the Fig. 14 position.

With this accomplished, the front slide 53 may be advanced by hand lever 55, Figs. 1, 2 and 9, to force the tap body fully up against the front stop 56.

With the front slide 53 latched in this holding position as shown in Figs. 2 and 9, the foot valve 44 may be tripped to admit pressure fluid to the front ends of cylinders 40, 41, to cause the pistons in these cylinders, through rods 36, 37, to laterally separate the slides 33, 34, as in Fig. 2, thus to cause the upper and lower pairs of fingers to stretch the cord throat laterally into the fully opened relation indicated in Figs. 3 and 15.

The back slide 61 carrying the contacts 25 and connected wires, is then advanced by hand lever 62 to project the contacts and attached wires fully into the opened tap body, substantially as shown in Fig. 2.

Hand levers 51, 52, may then be thrown up into the Fig. 7 position to collapse the spreader fingers vertically, and pressure in the cylinders released to permit the pistons, under impulse of the springs 42, to return toward the Fig. 1 position to the extent permitted by the entered contact projecting blades 65.

The front hand lever 55 may then be released by tripping latch lever 59, Fig. 1.

The back lever 62 may then be further advanced to push the partially collapsed tap body forwardly off the projecting ends of the partially collapsed spreader fingers 29, 30, 31, 32.

As the tap body is thus forced forwardly off the ends of the spreader fingers, it will collapse and close in abutting engagement over the ends of these fingers, substantially as indicated in Fig. 16, so that said body in its nearly fully collapsed condition will bear against the ends of these fingers and be thereby held while the contact inserting blades 65 are fully withdrawn by a backward retracting movement of hand lever 62.

The finished tap is thus stripped from the spreading and holding mechanism, leaving the mechanism in the fully opened relation indicated in Fig. 1, ready to receive and act upon the next tap.

What is claimed is:

1. A tap assembling machine comprising laterally

separable pairs of spreader fingers arranged to have the cord receiving end of an elastic tap body engaged thereover, the fingers of each laterally separable pair being vertically separable, means for effecting the vertical

5 separation of the fingers of each pair including vertically movable slides having hand levers for shifting the same in opposite directions, means for effecting lateral separation of said pairs of fingers to effect full expansion of the cord receiving end of the tap body and including laterally shiftable slides on which said vertically movable slides are mounted and means for effecting insertion of tap contacts through the fully opened cord receiving opening of the tap, including a slide having means on the front of the same for holding tap contacts and operable to

15 ward the back of said spreader fingers to carry said contacts into the position they are to occupy in the tap and a front slide operable toward the front of said spreader fingers to force and hold the tap in position on said spreader fingers while the contacts are being entered in 20 the tap body from the back.

2. A tap assembling machine comprising two laterally separable pairs of spreader fingers arranged to have the cord receiving end of an elastic tap body engaged thereover, the fingers of each laterally separable pair being vertically separable, means for effecting the vertical separation of the fingers of each pair, interconnected means for effecting lateral separation of said pairs of fingers and of the fingers of each pair to effect full expansion of the cord receiving opening and then relative collapsing movement of the fingers, means for effecting insertion of tap contacts through the fully opened cord receiving opening of the tap, including a slide having means on the front of the same for holding tap contacts and operable toward the back of said spreader fingers to carry said contacts into the position they are to occupy in the tap and a front slide operable toward the front of said spreader fingers to force and hold the tap in position on said spreader fingers while the contacts are being entered in the tap body from the back, the collapsing movement of all four of said spreader fingers permitting the tap body to close over the inserted contacts and said slide for inserting tap contacts having further advancing movement for stripping the tap body with the contacts inserted therein, off the spreader fingers.

3. A machine for assembling contacts and connected wires into a stretchable tap body, comprising spreader fingers insertable in the cord outlet of an elastic tap body separable in two different directions, means for effecting separation of said spreader fingers in said two different

40 directions and means for inserting tap contacts and attached wires into said tap body while spread in said two different directions, including a back slide provided with means for temporarily, releasably holding the tap contacts and attached wires and having movement to

55 carry said contacts through the spread-apart spreader fingers into seated position within a spread tap body and a front slide having movement toward the tap body to engage the same at its end remote from its said cord outlet for holding the tap body on the spreader fingers

60 during said spreading and stretching operations and a machine base having guideways for said slides for guiding them to move toward and away from the zone of operation of the spreader fingers.

4. A machine for assembling contacts and connected wires into a stretchable tap body, comprising spreader fingers insertable in the cord outlet of an elastic tap body separable in two different directions, means for effecting separation of said spreader fingers in said two different

70 directions and means for inserting tap contacts and attached wires into said tap bodies while spread in said two different directions, including a back slide provided with means for temporarily, releasably holding the tap contacts and attached wires and having movement to

75 carry said contacts through the spread-apart spreader

fingers into seated position within a spread tap body and a front slide for holding the tap body on the spreader fingers during said spreading and stretching operations, and a releasable latch for temporarily retaining said front slide in said contact and wire inserting operation and said back slide having an advancing movement toward said front slide and engageable in such movement with the tap body on the spreader fingers for stripping the tap body with the contacts and wires inserted therein, off said spreader fingers after said front slide has been released by 10 said latch.
